UNITED STATES PATENT OFFICE.

GUSTAV N. MEVES, OF ST. LOUIS, MISSOURI, ASSIGNOR TO THE BENBOW-BRAMMER MANUFACTURING COMPANY, OF ST. LOUIS, MISSOURI, A CORPORATION OF MISSOURI.

MECHANICAL MOVEMENT.

No. 890,156.

Specification of Letters Patent.

Patented June 9, 1908.

Application filed August 10, 1906. Serial No. 329,994.

To all whom it may concern:

Be it known that I, GUSTAV N. MEVES, a citizen of the United States, of St. Louis and State of Missouri, have invented certain new 5 and useful Improvements in Mechanical Movements; and I do hereby declare that the following is a full, clear, and exact description thereof, reference being had to the accompanying drawings, and to the letters of 10 reference marked thereon, which form a part of this specification.

This invention relates to a mechanical movement and it refers more specifically to an improved construction in mechanisms for 15 converting a continuous rotary movement of one shaft into a rotary reciprocating, or to and fro turning, movement of another shaft. Mechanism of this character is adapted for employment whenever it is desired to convert 20 a continuous rotary movement of one shaft into a rotary reciprocating movement of another part or shaft and is especially applicable to washing machines for imparting rotary reciprocating movement to the agitator shaft of a washing machine from the continuously 25 rotative driving shaft thereof.

The invention consists in the matters hereinafter set forth and more particularly pointed out in the appended claims.

30 In the drawings:—Figure 1 is a side elevation, with parts shown in section, of a mechanism embodying my improvements. Fig. 2 is an end view of the parts, looking in the direction indicated by the arrows 2—2 of Fig. 35 1. Fig. 3 is a cross-section, taken on line 3—3 of Fig. 1. Fig. 4 is a cross-section, taken on line 4—4 of Fig. 5. Fig. 5 is a detail sectional view illustrating a modification 40 of the jointed connection between the driving wheel hub and shaft. Fig. 6 is a plan view of the detachable part of the hub of the driving wheel of the mechanism shown in Fig. 5, removed from the other parts of the machine. Fig. 6^a is an end elevation of the hub of the 45 driving wheel shown in Fig. 5. Fig. 7 is a view similar to Fig. 1 illustrating a further modification of the invention. Fig. 8 is a cross-section taken on line 8—8 of Fig. 7. Fig. 9 is an end view of the hub of the driving 50 wheel shown in Fig. 7. Fig. 10 is a cross-section, taken on line 10—10 of Fig. 7. Fig. 11 is a side elevation, with parts broken away, of the detachable portion of the hub of the driving wheel shown in Fig. 7. Fig. 12 is a

fragmentary sectional view of a modified 55 form of the driving wheel hub to produce the jointed or flexible connection of the driving shaft with said hub.

As shown in the drawings,—A designates the continuously rotative shaft of the mechanism, and B the driven shaft to which is imparted rotary reciprocating movement from the continuously rotative shaft A. The shaft B may constitute the upper end of the agitator shaft of a washing machine. 60

C designates what may be the cover or upper wall of the tub of the washing machine, upwardly through which the shaft B extends.

D designates the supporting frame for the mechanism, which is formed to provide at 70 one end a portion D¹ containing upper and lower bearings d d¹ for the shaft B, and at its other end a horizontal bearing sleeve d².

E designates a driving wheel through the medium of which the shaft A is rotated. 75 Said wheel is provided with a horizontally arranged tubular hub E¹ that is rotatively mounted in the bearing sleeve d². As shown in Figs. 1 to 3, inclusive, said hub is made an integral part of the driving wheel E and its 80 cylindric bearing in the sleeve d² is formed between a shoulder e on the hub and a removable shoulder, as the nut e¹, which has screw-threaded engagement with the inner 85 end of the hub and bears against the inner end of the bearing sleeve d². Said nut e¹ may be secured to the hub in any suitable manner, as by means of a lock or jam-nut e². The bearing sleeve d² is provided with an oil aperture d³ through which a lubricant may 90 be applied to the bearing between the rotative hub and said sleeve.

The driving shaft A is provided at its inner end with a pinion A¹ adapted to alternately engage the upper and lower sides of radial 95 teeth, arranged in a circular series and carried by the shaft B, whereby the continuous rotation of the shaft A is converted into a rotary reciprocating movement of the shaft B. The said teeth or gears are, in this instance, formed by pins F F carried by the shaft B. As herein shown, said pins F are formed on a cylinder F¹ that is non-rotatively fixed to the shaft in any suitable manner. The inner end of the shaft A which carries 100 the pinion A¹ is adapted to rise and fall when passing from one side of the row of teeth or gears to the other, and, for this purpose is 105

connected at its outer end with the hub by a joint or connection located inside the hub permitting said rising and falling movement of the outer or pinion carrying end thereof.

- 5 The pinion A¹ is held in meshing engagement with the teeth F carried by the shaft B, when engaged with the upper and lower sides of said teeth, and also when passing around the curved row of teeth, by engagement of the extended end a of the shaft A with a cam groove F² formed in the exterior face of the cylinder F¹, extending above and below and around the ends of the series of teeth. The said extended end a of the shaft 10 A, as well also as the teeth F of the cylinder, may be provided with roller bearings to facilitate the action of said parts one upon the other.

The radially extending, curved series of 20 teeth, coöperating with the pinion in the manner described, constitute, in effect, a double row of teeth or cogs carried by the rotary reciprocating shaft B that are adapted to be alternately engaged by the pinion during 25 the continuous rotation and rising and falling movement of the inner end of the shaft A, in a manner to rotate the shaft B first in one direction and then in the other; it being obvious that the upper and lower 30 sides of said radially extending pins constitute such double row of teeth in the same manner as though said sides of the teeth were formed on separated radial extensions of the cylinder F¹. So far as the present 35 invention is concerned, therefore, the arrangement of the teeth, adapted to be alternately engaged by the pinion to effect the rotary reciprocating movement of the shaft B, may be widely varied from the arrangement 40 herein shown, while capable of ready adaptation to the improvements constituting my invention.

Referring now to the jointed connection between the outer end of the rising and falling, continuously rotative driving shaft A and the hub E¹ of the driving wheel, the said parts are made as follows: The connection herein shown between said parts embraces, in general terms, a ball and socket joint 50 located within said hollow hub of the driving wheel in the plane of the wheel, one of said parts being provided with a spherically curved head or ball and the other part with a corresponding socket which permits the shaft 55 A to rise and fall in a plane parallel with the shaft B. As herein shown, said shaft A is provided at its outer end with a spherical head or ball A² which is formed integral with the shaft. When said head or ball is formed 60 integral with the shaft, the socket within the hub to receive the ball or head comprises a two-part socket. In this instance, said socket is formed partially on the outer face or side of an interior flange e³ of the hub and the inner end of a nut E² that enters the outer open

end of the hub and is exteriorly screw-threaded to engage interior screw-threads in said outer end of the hub, the adjacent faces of the nut and flange being spherically concave to correspond to the spherical contour of the head or ball A². Said flange e³ surrounds an opening e⁴ in the hub through which extends the shaft A, and said opening, as well as the bore of the hollow hub, is made of sufficient diameter to permit the required rising and falling movement of the shaft A. The said ball or head and its socket need not be made truly spherical, it being necessary that they be made with cylindric surfaces only to provide the required flexibility of the joint to 75 permit the rising and falling movement of the outer or pinion end of the shaft.

In assembling the parts of the hub the driving wheel is inserted into its bearing through the outer end of the bearing, and the shaft A is inserted through the hub before the pinion A¹ is fixed thereto. Thereafter the nut E² is fitted in place to complete the socket which incloses the ball or headed end of the shaft. The said head or ball of the shaft A has interlocking connection with the hub whereby rotative movement of the hub is transmitted to the shaft. This is effected in the present instance by means of lugs a³ a³ which extend oppositely from said head and engage oppositely located, parallel grooves e⁵ formed in the cylindric side walls of the hub, as shown in full lines in Fig. 3 and in dotted lines in Figs. 1 and 2. The said nut E² constitutes, in effect, a part of the hub, but is shown as made separate therefrom and removably secured thereto for the purpose of facilitating the assembling of the joint when the head or ball A² is formed an integral part of the shaft A. The said shaft A has guiding engagement in a vertical guide slot d⁴ formed in the bearing frame D¹ to hold the shaft and pinion laterally in operative position. Said frame D¹ may constitute a portion of a casing which incloses the intermeshing gears of the continuously rotative and the rotary reciprocating shaft. When so constructed, the frame D¹ may have the form of a hemi-spherical casing, to which is hinged a like member D², such construction being generally similar to the casing shown in the pending application of John Edens, filed December 1st, 1905, Serial Number 289,836. The said bearing frame or casing may be provided with a flange or web d⁵, as shown in Fig. 1, adapted to engage the hub of the pinion A¹ to hold said pinion and the shaft from being forced away from the cylinder carrying the teeth or pins F.

In the operation of the mechanism described, the shaft A is turned continuously in one direction through the medium of the hand-wheel E. The continuous rotation of said shaft acts through its meshing engagement with the teeth on the cylinder F¹ to 125

turn the shaft B in one direction until said pinion reaches one end of the series of teeth, and the guiding engagement of the extension a of said shaft with the cam groove F^2 causes 5 the pinion to move from one side of the teeth to the other, and when said pinion has passed into engagement with said other side of the teeth the direction of rotation of the shaft B is reversed. The continuous rotation of the 10 shaft A, therefore, imparts a to-and-fro turning reciprocatory rotation to the shaft B, the shaft A and its pinion rising and falling at the end of the rotary reciprocating movement of the shaft B to engage the alternate 15 sides of the teeth.

The jointed connection of the shaft A with the hub of the wheel permits the shaft and pinion to readily adapt themselves to the action of the teeth carried by the shaft B in a 20 manner to minimize the friction of the working parts. The said connection is also constructed in a manner to produce a durable joint which has ample strength to transmit movement from the wheel to the shaft A. 25 The said construction, while producing the foregoing desirable results, enables the mechanism to be materially shortened over all. While providing ample length to the shaft A, it avoids an objectionable amplitude of 30 swing of said shaft, and an objectionable angular movement of the shaft about its axis of oscillation.

Instead of forming the socket which receives the ball or headed end of the shaft A 35 on a part integral with the wheel, the said part may be made separate from and detachably fitted to the wheel to constitute a two-part hub. This construction is shown in Figs. 4 to 6, inclusive, and is made as follows: E³ designates a separate, elongated sleeve portion of the hub which fits closely 40 within the hub E⁴ proper of the wheel E and is interlocked thereto by means of a latch G that is fastened by means of a screw g to said 45 hub, and is provided with a lug or detent g^1 that extends through registering openings in the hub and detachable sleeve, the opening in the sleeve being designated by the reference letter e^{15} (Fig. 6). In this construction, 50 the sleeve is inserted into the hub and the bearing from the inner end of the bearing. In this instance, the separable part E⁶ of the 55 socket, corresponding with the nut E², shown in Fig. 1, is formed integral with the wheel- 60 hub and the sleeve E³ is interlocked therewith by means of lugs e^8 at the end thereof which enter suitable notches in said part E⁶, as shown in Figs. 5 and 6^a. In other respects the construction of the joint is generally similar to that shown in Figs. 1 to 3, inclusive, and such like parts bear the same reference letters.

In the construction shown in Figs. 7 to 11, inclusive, antifriction bearing members are 65 interposed between the driving wheel and

the bearing d^2 . In this construction, a sleeve E⁵ is provided, corresponding with the sleeve E³ shown in Figs. 5 and 6, which is inserted and held removably in the hub E⁴. The said sleeve is provided with a reduced 70 cylindric portion e^9 located between the inner flange e^6 and a shoulder e^{10} engaging the outer end of the bearing sleeve d^2 . The reduction of said sleeve forms an annular 75 chamber between the sleeve and bearing in which are located a plurality of cylindric rollers H which reduce the rotative bearing friction between the said hub and said bearing. The separable sleeve of the hub is interlocked with the inner portion E⁴ of the 80 hub by lugs e^{11} which enter the grooves e^5 which receive the lugs a^3 of the head A² of the driving shaft.

In the construction shown in Fig. 12, the driving wheel E⁷ is provided with a closed 85 ended hub E⁸ generally similar to that shown in Fig. 5, said hub embracing in its construction a separable sleeve E⁹ that is fixed to the main body of the hub by means of a setscrew E¹⁰ extending through and having 90 screw-threaded engagement with the hub and entering a socket e^{12} in the removable part of the hub. The closed end of the hub is formed to provide a spherically concave, inwardly facing recess e^{13} which co-operates 95 with a like outwardly facing recess on an interior flange e^{14} of the part E⁹ of the hub to form a socket to receive the ball or head A² of the shaft A. In other respects the construction of the parts may be the same as 100 that of the constructions before described.

In the several constructions shown in Figs. 4 to 12 inclusive the sleeves illustrated therein constitute parts or members of the hubs, each of said hubs embracing a member integral with the wheel and a detachable or sleeve member which constitutes the bearing portion of the hub.

I claim as my invention:—

1. In a mechanical movement, the combination with a bearing frame, of a driving wheel provided with an elongated tubular hub rotatively mounted in the frame, a driven shaft capable of rotary reciprocatory motion, a continuously rotative driving 110 shaft, and intermeshing gears on the driving and driven shafts, said continuously rotative shaft being provided on its outer end with a ball or head and being adapted to be inserted through the hub from the outer end 115 of the latter, the hub being provided with an internal, outwardly facing spherical surface adapted for engagement by said head, and with a part extending into the outer end thereof having an inwardly facing spherical 120 surface which co-operates with said outwardly facing spherical surface to provide a socket to receive said head or ball, the parts 125 being so arranged that the inner end of the continuously rotative or driving shaft is ca- 130

pable of a rising and falling movement and imparts through the continuous rotation thereof a rotary reciprocatory movement to the driven shaft.

- 5 2. In a mechanical movement, the combination with a bearing frame, of a driving wheel provided with an elongated tubular hub rotatively mounted in said frame, a driven shaft mounted in said frame and capable of rotary reciprocatory movement, a rotative driving shaft extending at one end into said hollow hub and provided between the ends of the hub with a head or ball non-rotatively fixed to said hub, said hub being 10 provided between its ends with an internal apertured flange through which said driving shaft extends and with an outwardly facing spherical surface engaging said head, a nut entering the outer end of said hub and having 15 a detachable connection therewith and provided in its inner end with a spherical surface which co-operates with the outwardly facing spherical surface of said flange to provide a socket for said head or ball of the driving shaft, thereby constituting a joint between the shaft and hub permitting the inner end of the shaft to rise and fall, and intermeshing gears on the driving shaft and the driven shaft for imparting to the latter a 20 rotary reciprocatory movement through the continuous rotation of the driving shaft.
3. In a mechanical movement, the combination with a bearing frame, of a driving wheel provided with an elongated tubular hub rotatively mounted in said frame, said hub including a sleeve that is removably mounted in the wheel, a driven shaft capable of rotary reciprocating movement, a driving shaft extending into said removable sleeve 25 of the hub and connected with said sleeve by a ball and socket joint located within the sleeve between the ends thereof and intermeshing gears on said driven shaft and the driving shaft for imparting a rotary recipro-

catory movement to the driven shaft through 45 the continuous rotation of the driving shaft.

4. In a mechanical movement, the combination with a bearing frame, of a driving wheel provided with an elongated tubular hub rotatively mounted in the frame, said hub including a sleeve that is removably mounted in the wheel, antifriction rollers interposed between said hub and bearing, a driven shaft capable of rotary reciprocatory movement, a driving shaft extending into 50 said removable sleeve of the hub and connected with said sleeve by a ball and socket joint located within the sleeve between the ends thereof and intermeshing gears on the driven shaft and driving shaft for imparting 55 a rotary reciprocatory motion to the driven shaft through the continuous rotation of the driving shaft.

5. In a mechanical movement, the combination with a bearing frame, of a driving 60 wheel provided with an elongated tubular hub rotatively mounted in the frame, said hub including a sleeve which is mounted in the wheel, means removably and non-rotatively fixing the sleeve in the wheel, a 65 driven shaft capable of rotary reciprocatory motion, a driving shaft extending into said removable sleeve of the hub and connected with said sleeve by a ball and socket joint located within the sleeve between the ends 70 thereof, and intermeshing gears on the driven shaft and driving shaft for imparting a rotary reciprocatory motion to the driven shaft through the continuous rotation of the driving shaft.

In testimony, that I claim the foregoing as my invention I affix my signature in the presence of two witnesses, this sixth day of August, A. D. 1906.
